Patented Feb. 1, 1921.

UNITED STATES PATENT OFFICE.

ALEXANDER M. PASNIK, OF NORWICH, CONNECTICUT.

SALT-SHAKER.

1,366,929.

Specification of Letters Patent.

Patented Feb. 1, 1921.

Application filed October 6, 1920. Serial No. 415,113.

To all whom it may concern:

Be it known that I, ALEXANDER M. PASNIK, a citizen of the United States, residing in the city of Norwich, State of Connecticut, 5 have invented a new and useful Improvement in Salt-Shakers, of which the following is a specification.

The object of the invention is to provide a salt-shaker which will always run freely 10 and controllably, irrespective of conditions tending to cause clogging or lumping, and which is simply and advantageously constructed. To this end, the invention may be said to consist in the novel device, and 15 the parts, improvements and combinations hereinafter described in preferred embodiment, and more particularly pointed out in the appended claim.

In the accompanying drawings, forming 20 a part hereof:

Figure 1 is an elevation;

Fig. 2 is a central vertical section;

Fig. 3 is a view corresponding to the 25 lower part of Fig. 2, with the plug or valve open; and

Figs. 4 and 5 are horizontal sections on the lines 4—4 and 5—5 of Fig. 2.

The shaker has an upright holder 1, the salt chamber 2 of which has a sloping bottom 3 with a central throat or discharge opening 4. A base 5 below the throat contains a flaring mouth 6.

The throat is normally closed by a tapered plug 7, the lower portion of which seats upwardly against the throat, this portion being preferably formed with an annular groove in which is held a truncated conical washer or packing gasket 8 of suitable material. Above or inwardly of the seating 40 portion is a series of transverse corrugations 9, of diminishing diameters, said corrugations serving to break up lumps when the plug is depressed so as to open an annular outlet between it and the throat, the

plug being worked back and forth if need be to produce the desired flow. The corrugations also constitute baffles to prevent too copious a discharge when the salt is dry and in good condition, and by reason of the taper or graduation the size of the outlet 50 is variable according to the extent to which the plug is projected within the mouth.

The plug is on the lower end of a spindle or connection 10 passing through the salt-chamber, and having a projecting plunger 55 11 secured to its upper end, whereby the plug is unseated by finger pressure exerted against a spring 12, which serves to close the valve.

A ring 13 fixed to the open upper end of 60 the body of the holder carries a central vertical spring barrel 14, in which the plunger is guided; and the top is closed by a removable cap 15 having a central opening to accommodate the spring barrel. Said cap is 65 retained by a bayonet joint formed by lateral projections 16 on the ring 13 and corresponding notches 17 in the lower rim of the cap, communicating with the interior of an annular pressed-out bead 18 in which 70 the projections are locked by turning the cap.

What is claimed as new is:

A shaker comprising a holder having a 75 throat in the bottom, a longitudinally movable plug in the throat, an open ring fixed to the open upper end of the body of the holder and carrying a central spring barrel, and a plunger operative in the spring barrel and connected with the plug, in combination with a removable cover fitting centrally around the spring barrel and having an outer rim encircling the fixed ring, said 80 rim having a pressed-out circumferential bead and a slotted entrance thereto from 85 the lower edge of the rim and a projection on the ring adapted to lock behind said bead.

ALEXANDER M. PASNIK.
